UNITED STATES PATENT OFFICE.

NAPOLEON B. DOUGLASS, OF OAKLAND, CALIFORNIA.

FOLDING BED.

Application filed April 27, 1921. Serial No. 464,812.

To all whom it may concern:

Be it known that I, NAPOLEON B. DOUGLASS, a citizen of the United States, residing at Oakland, in the county of Alameda and State of California, have invented new and useful Improvements in Folding Beds, of which the following is a specification.

This invention relates to folding beds and has for its object to provide a hinge connection for the supporting legs, which is easy and inexpensive to construct and which will act automatically to lock the legs in extended position and automatically unlock itself when the weight of the bed frame is removed from the legs in the act of folding the bed.

One form which my invention may assume is exemplified by the following described illustration in the accompanying drawings in which Fig. 1 shows a vertical, sectional view of the outer part of a folding bed illustrating a supporting leg in extended position. Fig. 2 shows an end elevation of the bed. Fig. 3 shows a sectional view in elevation of the parts in folded position. Only so much of a bed frame as is necessary to an understanding of the present invention has been illustrated. This bed frame includes side rails 10 pivotally mounted at their forward ends for folding movement and carrying at their outer end a rigid foot piece 11. A supporting leg 12 is connected to each side rail for folding movement. The hinge connection between the leg and side rail embodies the following construction: the upper end of each leg is flattened, as shown at 13, and into this flattened portion a longitudinal slot 14 and a transverse slot 15 are cut. Through these slots extends a rectangular hinge pin 16 fixed to the side rail 10, or other part of the bed frame. The rectangular slot 14 is somewhat longer than the pin 16 and when the bed is extended and the leg 12 is resting on the floor and in alignment with the foot piece 11, the hinge pin 16 will seat in the bottom of the slot 14 by reason of the weight imposed thereon by the bed frame. A segment 17 is cut away between the slots at the upper inside corner and a similar segment 18 is cut away between the slots at the lower outside corner except that the last named segment terminates short of the bottom longitudinal

slot so that when the hinge pin 16 is seated in the bottom of the slot, the leg is locked against swinging movement. To enable the leg to be folded, the bed frame must first be raised to allow the hinge pin 16 to move to the upper end of the longitudinal slot 14 whereupon the leg will be free to swing inwardly to folded position.

The present hinge is easy and inexpensive to construct and acts automatically to lock the leg against movement of any kind when the bed frame is extended. Therefore, the leg will be held against accidental displacement. Likewise, when the weight of the bed is removed from the legs and the latter are suspended from the bed frame in the act of folding the bed, the hinge connection is automatically unlocked so that the legs are free to swing to folded position.

Various changes in the construction and arrangement of the several parts above shown and described may be employed without departing from the spirit of my invention as disclosed in the appended claims.

Having thus described my invention, what I claim and desire to secure by Letters Patent is:

1. A folding bed comprising a frame pivotally mounted at one end for folding movement, a pendant supporting leg at the opposite end of the frame and a hinged connection between the leg and frame comprising a pin elongated in the direction of the axis of the leg and fixed upon one of the hinged members, the other member having vertical and horizontal slots crossing each other, the material at the upper inside corner and the lower outer corner between the cross slots being cut away to allow the pin to turn therein through an arc of approximately 90° when the leg is hanging pendant and the vertical slot being extended slightly at one end to form a pocket or seat for the pin when the frame is resting on the leg whereby to lock the leg against swinging movement.

2. In a folding bed, a bed frame, a supporting leg for the foot of the bed frame formed of tubular stock and a hinge between said leg and the bed frame formed by flattening the tubular member of the leg and providing said flattened portion with an opening consisting of longitudinal and transverse

slots crossing each other—the material at the upper inside corner and the outer lower corner between the crossed slots being cut away, and a hinge pin elongated in the direction of the axis of the leg fixed to said bed frame and extending through said opening—said hinge pin being shorter than the longitudinal slot and adapted to rest in an extension at the lower end of the said longitudinal slot when the bed frame is in extended position and supported by the leg, whereby to lock the leg against swinging movement.

NAPOLEON B. DOUGLASS.
